UNITED STATES PATENT OFFICE.

REGINALD F. R. AMOR, OF LEYTONSTONE, LONDON, ENGLAND.

PORTABLE CASING FOR TALKING MACHINES.

Application filed November 3, 1921. Serial No. 512,567.

To all whom it may concern:

Be it known that I, REGINALD FRANK ROBERT AMOR, a subject of George V, King of Great Britain and Ireland, residing at 5 741 High Road, Leytonstone, in the county of London, England, have invented certain new and useful Improvements in and Relating to Portable Casing for Talking Machines, of which the following is a specification.

10 This invention relates to gramophones and the like, and is intended for application primarily to portable gramophones mounted in foldable cases. The invention has for chief 15 objects to enable the gramophone and case to be folded into smaller compass than heretofore, and to provide an improved construction of combined horn and sound diffuser or reflector.

20 In carrying out this invention, I hinge the motor-box and the diffuser or reflector to the case in such a manner that in order to close the case the reflector is first swung outwards, the motor-box is then swung inwards so as 25 to bring the turntable close up against the back of the case, the tone-arm is next swung underneath the sound diffuser or reflector, and the latter is then folded back into the case so that the tone arm and a portion of 30 the turntable are accommodated in a space behind the reflector.

35 The horn passes through one side or portion of the sound diffuser or reflector, being conveniently and, if desired, permanently fixed thereto by means of a flange with which it may be provided. The horn is arranged so as to deliver the sound waves into the inner end of the sound diffuser or reflector. The tone-arm has its inner end 40 swivelled to the open end of the horn.

In the drawings—

Fig. 1 is a front elevation showing the case open and, in full lines, the motor-box and tone arm folded outwards in the position 45 for playing.

Fig. 2 shows the motor-box and tone-arm in side elevation and the reflector and rear portion of the case in vertical section.

Referring to the drawings, the motor box 50 *a* is hinged at its lower rear edge *a*¹ to the lower front edge of the case *b* and it is also made of such width from back to front that its top and the turntable *c* overhang it at the front to form a recess which, when the 55 case is closed, is occupied by the tone-arm, the sound-box and the turntable. Its front

portion may be provided with rubber or like buffers (not shown) on which it rests when opened out from the case.

When the motor box is folded outwards, 60 its base *a*² forms a continuation of the lower end of the case *b* and it may be maintained against accidental displacement from that position by means of a spring catch or the like which is fixed to the motor-box and engages the adjacent side of the case.

The sound diffuser or reflector *d* is hinged at *d*¹ to the top front edge of the case and its shape is preferably substantially frusto-pyramidal so that it fits snugly into the case. 70 The inner end of the sound diffuser or reflector terminates in a pyramid *d*² whose apex is directed outwardly.

The portion of the case above the motor-box is provided at each side with a vertical 75 door *b*¹ hinged thereto and extending, when closed, approximately halfway across the case.

Dealing now with the combined horn and sound diffuser or reflector, the horn *e* passes 80 through the lower portion of the sound diffuser or reflector and is fixed thereto by means of a flange *e*¹ with which it is provided. The portion of the horn on the underside of the sound diffuser or reflector is 85 swivelled at *e*² to the upper end of the tone arm *f* so that the latter can move sideways as the needle *g*, carried by the reproducer, travels, in the usual way, over the record *h*. The sound waves from the upper open end of 90 the horn impinge on the pyramid *d*², and are deflected thereby forwards.

It will be obvious that the horn may be combined with the sound diffuser or reflector in various other ways. For example, it may 95 be attached to the underside of the sound diffuser or reflector and be bent or otherwise shaped so as to extend around the front edge of the sound diffuser or reflector; this arrangement renders any cutting away of the 100 sound diffuser or reflector unnecessary. Or again, the horn may be let into a recess or slot formed in the front edge of the sound diffuser or reflector. The point at which the horn passes through or around the front 105 edge of the sound diffuser or reflector may be at one side or at the top of the sound diffuser or reflector; in either case an increased length of tone arm is obtained with consequent increase in richness of tone produced 110 by the gramophone.

The sound diffuser or reflector is pre-

vented from becoming accidentally displaced from its inner position by means of spring catches d^3 or the like.

5 Rotatably mounted on a pin a^6 , projecting below the overhanging top of the motor-box, is a needle tray a^7 , which can be swung outwards for the supply of needles. When not in use, the tray is swung inwards into the position shown in Fig. 2 in which position 10 the overhanging portion of the motor box constitutes a lid for the needle tray.

In order to fold up the gramophone and case, the needle-tray is first swung in underneath the motor-board and then the winding-handle a^4 is placed in a spring-clip a^5 provided at the front of the motor-box, as shown in Fig. 1, and the sound diffuser or reflector d is drawn outwards into some such position as that shown in broken lines in 15 Fig. 2, so as to provide clearance for the motor-box. The tone-arm is next swung backwards behind the lower sloping portion of the sound diffuser or reflector, and the sound-box and swan-neck are folded back 20 thereon. The tone-arm is then drawn forwards a little and is held in the position shown in broken lines by means of a spring-catch d^4 or the like, which is fixed to the sound diffuser or reflector and engages the 25 swan-neck. The motor-box is now swung upwards and inwards into the position shown in broken lines in Fig. 2, and the sound diffuser or reflector, tone-arm, etc., are swung downwards and inwards, as illustrated, and are held in that position by 30 means of the catches d^3 . It will be seen from an inspection of Fig. 2 that the triangular space behind the lower portion of the sound diffuser or reflector is now occupied by the 35 overhanging portion of the motor-board and turntable, and also by the tone-arm, etc., which arrangement results in considerable economy of space and compactness of construction.

40 In its closed position, the base a^2 of the motor box closes the lower portion of the case. The doors b^1 are now closed, one after the other, one of them being provided with a rabbet into which the other one fits, and the 45 lower edges of both doors fitting into a rabbet a^8 provided in the motor box. Finally, a catch b^2 is turned down over the top edge of the doors. Thus, by means of the catch b^2 and the rabbets, the front of the 55 case becomes securely closed.

The case is provided at one side with a carrying handle k , so that, in its closed position, it appears like an ordinary attaché case.

60 The sound diffuser or reflector may, if desired, be hinged at one side instead of at the top of the case.

65 The sound diffuser or reflector may be made of wood, metal, fibre or other suitable material and may be made of any suitable shape.

The arrangement of combined horn and sound diffuser or reflector is applicable for use with other gramophones and the like besides the foldable gramophone above described.

70 It is to be understood that the swivelling of the horn to the tone arm may, if desired, be effected within instead of below the sound diffuser or reflector, also that the flange e^1 75 may be arranged below instead of inside the sound diffuser or reflector.

I claim:—

1. A gramophone-cabinet comprising a casing, a motor-box hinged at its lower rear edge to the lower front edge of said casing, a sound diffuser or reflector hinged to said casing, and a hinged tone-arm, the parts being so arranged that, in their open position the bottom of the motor-box is flush with the bottom of said casing, and in their closed position the motor-box lies completely within the casing, and the tone-arm lies between the motor-box and the sound diffuser or reflector.

80 2. A combined gramophone and cabinet comprising a casing, a motor-box hinged at its lower rear edge to the lower front edge of said casing and containing a motor and carrying also a turntable which overhangs the front of the motor-box, a sound diffuser or reflector hinged to said casing, and a tone-arm swivelled on said sound diffuser or reflector, the parts being so arranged that, in their open position, the bottom of the motor-box is flush with the bottom of the casing and in their closed position the motor box lies completely within the casing and the tone-arm lies in the space between the motor-box and the lower portion of the sound diffuser or reflector.

85 3. A combined gramophone and cabinet comprising a casing, a motor-box hinged at its lower rear edge to the lower front edge of said casing the same containing a motor and carrying a turntable, a sound diffuser or reflector hinged to said casing, a horn fixedly attached to and extending through the diffuser or reflector, a tone arm maintained in movable engagement with the horn, the parts being so arranged that, in their open position, the bottom of the motor-box is flush with the bottom of the casing and in their closed position the motor box lies completely within the casing and the tone-arm lies in the space between the motor-box and the lower portion of the sound-reflector.

90 4. In a portable casing for sound reproducing machines, comprising a receptacle which is open at its front when in use, a sound diffuser connected to the casing in such a manner as to be capable of swinging outward therefrom, a reproducer tone arm and horn associated with and maintained by the sound diffuser, the parts being so connected that the sound reproducer may be moved to 95 100 105 110 115 120 125 130

be positioned partly in the rear of the sound diffuser when it is moved outward, and a motor box which maintains a turntable, said motor box being connected with the receptacle to be moved within the same.

5. In a device of the character described, a casing having pivoted thereto a sound diffuser which is adapted to be swung beyond the open side of the casing, a horn fixedly 10 attached to the sound diffuser, an arm movably connected to the horn and adapted to be extended beyond the sound diffuser, a reproducer pivoted to the arm, a motor box and turntable support hinged to the lower 15 forward portion of the casing said box being and adapted to form a partial closure for the casing, doors hinged to the casing to complete the closure therefor when the parts

herein mentioned are positioned within said casing.

6. In a device of the character set forth, an open sided rectangular casing, a sound diffuser maintained by the casing and adapted to support a horn, a tone arm and a reproducer, the arm and reproducer being movably connected to the horn, a motor box associated with the casing and provided with an extended portion, and doors hinged to the casing to cooperate with the motor box to form a complete closure therefor.

In testimony whereof, I have signed my name to this specification in the presence of the subscribing witness.

REGINALD F. R. AMOR.
